UNITED STATES PATENT OFFICE.

JAMES M. TAYLOR, OF DUBOIS, PENNSYLVANIA.

DESIGN FOR A DISPLAY-RACK.

SPECIFICATION forming part of Design No. 26,931, dated April 20, 1897.

Application filed February 10, 1897. Serial No. 622,864. Term of patent 14 years.

To all whom it may concern:

Be it known that I, JAMES M. TAYLOR, a citizen of the United States, residing at Dubois, in the county of Clearfield and State of Pennsylvania, have invented and produced 5 a certain new and original Design for Display-Racks; and I do declare the following to be a full, clear, and exact description of the invention, such as will enable others skilled in the 10 art to which it appertains to make and use the same.

My invention relates to a new and original design for display-racks.

In the accompanying drawings, Figure 1 15 is a perspective view of the rack; and Fig. 2 is a side elevation.

A denotes the side pieces, and A', the connecting-bars. The lower ends of the side pieces have short laterally-projecting arms 20 B, connected by an arched cross-bar C, while the upper ends are provided with arms D, which curve downwardly, then project laterally beyond the outer ends of the lower arms B, and are provided with hooks.

The leading features of my design are the 25 connected side pieces having at their lower ends short outwardly-projecting arms and at their upper ends long arms which project outwardly and are provided with hooks.

What I claim is—

1. The design for a display-rack as herein shown and described.
2. The design for a display-rack, consisting of connected side pieces cross-bars connecting the side pieces, said side pieces having 35 laterally-projected arms at their lower ends, and laterally-projected arms at their upper ends, which project outwardly a greater distance than the lower arms, and which are provided with hooks, substantially as set forth. 40

In testimony whereof I hereunto affix my signature in presence of two witnesses.

JAMES M. TAYLOR.
